UNITED STATES PATENT OFFICE.

ALBERT R. SHATTUCK, OF NEW YORK, N. Y.

FEED-WATER REGULATOR.

SPECIFICATION forming part of Letters Patent No. 644,688, dated March 6, 1900.

Application filed May 1, 1899. Serial No. 715,090. (No model.)

To all whom it may concern:

Be it known that I, ALBERT R. SHATTUCK, of the city, county, and State of New York, have invented a new and useful Improvement 5 in Feed-Water Regulators, of which the following is a specification.

The object of my invention is to provide a simple form of automatic regulator for any controlling device, such as a cock or valve, 10 which is itself governed by variations in water-level in a steam-generator.

My invention consists in the combination of parts more particularly pointed out in the claims.

15 In the accompanying drawings, Figure 1 is a side elevation of my regulator, showing certain parts in vertical section. Fig. 2 is a side elevation showing my regulator attached in place upon the side of a steam-boiler. Fig. 3 20 is a detail view showing the mode of attachment of the flexible connecting-tubes at their ends.

Similar letters and numbers of reference indicate like parts.

25 *a* is a closed receptacle, shown as preferably made in two parts *b* and *c*, the flanges of which are connected by bolts *d*.

e is an internally-threaded lug on the receptacle *a*, which receives the rod *f*, to which 30 is pivoted the lever *g*, and to the lever *g* is pivoted the lever *h*, and the lever *h* is secured to any ordinary cock *i*, here shown arranged in a conduit *j*.

On the under side of the receptacle *a* is a 35 projection *k*, also internally threaded to receive a short rod *l*, in which there is a square slot *m*, which slot receives a pin *n*, secured to the end of a vertical rod *o*. The rod *o* extends down into the cylinder *p* and is provided 40 therein with a piston *q*, in which are apertures *r*. The cylinder *p*, which contains oil, has a cover *s*, in which are apertures *t*. Secured upon the rod *o* is a threaded sleeve *u*, which carries an annular flanged disk *v*, applied 45 to the threaded portion of said sleeve *u*. On the lower side of the cylinder *p* is a broad flange *w*, having an annular upward projection *x*. The lower end of a spiral spring *y* lies inside of the projection *x*, and said spring 50 surrounds the cylinder *p* and the rod *o*, and its upper end terminates just beneath the

flanged annular disk *v*. Connected to the pin *d* is a yoke *z*, which carries a ring *1*, which ring surrounds the vertical guide-rod *2*. Upon the upper and lower faces of the receptacle *a* and respectively upon the parts *b* and *c* are short tubular projections *3* and *4*. Each projection, as shown in Fig. 3, is provided with projecting rings or collars *5*. Similar flanged projections are mounted on 55 plates *6*, which plates are bolted to the side of the boiler *7*. Between the projections bolted on the boiler and the projections *3* and *4* extend flexible tubes *8* and *9*. The said tubes are secured to projections, as *3*, in the 60 manner shown in Fig. 3—that is to say, the end of the tube is carried over the fixed collars *5* on the projection *3* and then around the flexible tubes, and in rear of said collars are placed clamping-rings *10*. The said rings 65 consist simply of bands, the ends of which are drawn together by screws, as *11*. In this way the tubes *8* and *9* are tightly held upon the projections, even when considerable steam-pressure is in said tubes. Bolted to 70 the side of the boiler is a bracket *12*, having an arm *13*, to which is pivoted one end of the rod *14*. The other end of said rod is threaded and is received in a turnbuckle *15*.

16 is a rod also received in the other side 80 of turnbuckle *15* and connected to pin *d* by a yoke *17*. As shown in Fig. 2, this device is preferably placed on a bracket *18*, which is supported in any suitable way on the side of the boiler; but I do not limit myself to this 85 mode of support, as I may use any which is suitable to the purpose in view. So, also, I have shown the thing upon which this regulator directly acts, as a valve *i*, arranged in a conduit *j*; but it is to be understood that I 90 do not limit myself to the employment of a valve in a conduit to be operated by my said device; but instead of such a valve I may use any contrivance for regulating the flow of water, steam, or gas or for modifying the action 95 of any mechanical contrivance so long as the same can be done by moving a mechanical part first in one way and then in another or to greater or less degree in either direction.

The operation of my invention is as follows: 100 The flexible tubes *8* and *9* are connected, respectively, to the steam-space and water-

space of the boiler. Consequently the water in the receptacle *a* will normally stand at the same level as in the generator. It will be obvious that if the receptacle *a* descends the 5 cock *i*, through the linkage *f g h*, will be turned in one direction, while if the receptacle *a* rises the cock *i*, through the same linkage, will be turned in the opposite direction. If, therefore, for example, *j* be a conduit 10 connecting water, it is further obvious that I may use the descent of the receptacle *a* to turn off the water or the rise of that receptacle to turn on the water through the agency of the cock, or vice versa; or, again, for example, if *j* be a conduit conducting steam to a pump which pumps water into the boiler it is obvious that I may use the descent of the receptacle to turn off the steam or the rise of the receptacle to turn on the steam, thus stopping 15 or starting the pump, and thus increasing or decreasing the level of the water in the boiler. When the receptacle *a* descends, it does so against the opposing action of the spring *y* acting upon the flanged disk *r*. Assuming 20 the parts to be so arranged and ordered as that when the water in the boiler is at a determinate level—that is to say, in the position shown in Fig. 1—then if the water-level in the boiler rises more water will come 25 into receptacle *a* and will cause that receptacle to descend by gravity against the action of the spring *y*. The effect of this descent will then be through the levers *f g h* to turn the cock *i*, so as to shut off a further supply 30 of water, steam, or gas to the pump or boiler. When, however, the water-level in the boiler becomes lower, then the spring *y* will react to return the receptacle to its normal position, and thus through the levers to open the 35 valve *i* once more; or, assuming the parts again to be in the position shown in Fig. 1, the spring *y* being compressed to balance the water in the receptacle *a*, if the water-level in the boiler should first fall then the spring 40 would expand to raise the receptacle *a*, and hence open the valve *i* and allow a further supply of water to come into the boiler or steam to the pump, and thereafter when the water-level in the boiler has risen the receptacle *a* will descend, again bringing the parts 45 into the position shown in Fig. 1.

It will be seen, therefore, from what has been described that my device is a very sensitive regulator, depending wholly upon 50 changes of level of the water in the boiler. The pipes 8 and 9 are, as I have said, made of flexible tubing—such, for example, as heavy india-rubber and canvas or any other suitable material. Inasmuch as the pipes 55 have more or less transverse resiliency, I prefer to make them in arched form, as shown, the tube 8 being reversely arched to the tube 9. In this way whatever strain due to the 60 tendency of the pipes to become straight is counteracted by the opposing arches. In order to meet the thrust upon receptacle *a* due to the pressure of steam in the tubes 8 and

9, I provide the pivoted rods 14 and 16, united by the turnbuckle 15. Because these rods are pivoted, as shown, to the boiler they will 65 readily adapt themselves to the vertical displacement of the receptacle *a*, and, moreover, by means of the turnbuckle the length of the two rods 14 and 16 may be shortened to 70 adjust them to the tubes 8 and 9 and to the 75 desired distance of the receptacle *a* to the boiler 7. Inasmuch as the receptacle *a* is carried at the end of the arm formed by the rods 14 and 16, it is obvious that in moving it will traverse a curve. This is allowed 80 for by the pin *n* entering into the large slot *m* at the point of connection between the receptacle *a* and the rod *o*. The sleeve 1, which surrounds the guide-rod 2, is made somewhat 85 loose, so as to allow for this curvilinear movement of the receptacle.

The cylinder *p*, with the piston *q* attached to the lower end of rod *o*, constitutes a dash-pot. Its function is to prevent impressed vibration of the receptacle *a*, or, in 90 other words, to prevent the receptacle *a* having any other movement than that which is produced by the varying weight of water within it and the action of the spring outside. This arrangement of dash-pot, in combination 95 with the receptacle *a*, is of especial advantage when the device is placed upon steam-vehicles which traverse rough or even ordinary roads, the effect of the dash-pot being to prevent the receptacle *a* being unduly vibrated 100 in passing over obstructions or inequalities in the road.

I claim—

1. In combination with a steam-generator, a movable closed receptacle outside of said 105 generator, flexible pipes connecting said receptacle respectively with the steam and water spaces of said generator, a pivoted rod extending from said receptacle to said generator, a spring opposing the downward movement of said receptacle, and a regulating device controlled by and through the movement of said receptacle, substantially as described.

2. In combination with a steam-generator, the movable closed receptacle *a* outside of 115 said generator, the spring *y* opposing the downward motion of said receptacle *a*, the reversely-arched flexible pipes 8, 9 respectively communicating with the upper and lower portions of said receptacle and with 120 the steam and water spaces of said generator, the jointed rod 14, 16 extending between said pipes from said receptacle to said generator, and a regulating device controlled by and through the movement of said receptacle, 125 substantially as described.

3. The combination with a steam-generator of the movable closed receptacle *a* outside of said generator and communicating with the steam and water spaces thereof, the spring 130 *y* opposing the downward motion of said receptacle, jointed rod *o* extending downward from said receptacle and connected to said spring *y*, dash-pot actuated by said rod *o* and

a regulating device controlled by and through the movement of said receptacle, substantially as described.

4. The combination with a steam-generator of the movable closed receptacle outside of said generator, the guide 2 for said receptacle, spring y opposing the downward motion of said receptacle, jointed rod o extending downward from said receptacle and connected to said spring y, flexible pipes 8, 9 respectively communicating with the upper and lower

portions of said receptacle and with the steam and water spaces of said generator, the jointed rod 14, 16 extending from said receptacle to said generator, and a regulating device controlled by and through the movement of said receptacle, substantially as described. 15
